UNITED STATES PATENT OFFICE.

HARRY BREGMAN, OF LORAIN, OHIO, ASSIGNOR TO THE STEEL STAMPING COMPANY,
A CORPORATION OF OHIO.

MOP HEAD.

Application filed August 17, 1921. Serial No. 492,884.

To all whom it may concern:

Be it known that I, HARRY BREGMAN, a citizen of the United States, residing at Lorain, in the county of Lorain and State of Ohio, have invented certain new and useful Improvements in Mop Heads, of which the following is a specification.

This invention relates to mop heads, and more particularly to the means thereof for holding the rags.

Another object of the invention is to provide a mop head having clamping means of a corrugated design for gripping the rags.

Another object of the invention is to provide mop head clamping means of said character, which is of simple and inexpensive construction and easily made from stamped plate material and wire.

In order that the invention may be clearly understood, the same will be hereinafter fully described as illustrated in the accompanying drawings, and the novel features thereof will be distinctly pointed out in the appended claims.

Figure 1 is a front view of a mop head constructed in accordance with my invention,

Fig. 2 is a side view of the same,

Fig. 3 illustrates the rear half of the clamping member and a cross bar of the wire frame in spaced relation thereto, and

Fig. 4 is a cross sectional view taken on line 4—4 of Fig. 3.

Referring to the drawings 1 represents the handle, the lower end of which is reduced at 2 to leave a shoulder 3, and is slightly tapered to be driven into a socket 4 of a clamping member 5. This clamping member is formed of two complementary sides 6 and 7, which are stamped from plate material and fixed together by spot welding or other suitable means. The sides 6 and 7 form an elongated cupped out recess 8 with opposite transverse bulged out depressions 9, and the ends of said plates are bent in opposite direction to serve as guides 10 and 11 for a wire clamping frame 12. Said clamping frame is constructed from a single piece of wire and consists of sides 13 and 14 which are adapted to slide in the guides 10 and 11, and a cross bar 15 having corrugations at 16 for co-operating with the elongated cupped out recess 8 and the transverse bulged out depression 9 of the clamping member 5 for gripping rags therebe-

tween to hold them securely. The free ends of the sides 13 and 14 of the clamping frame terminate in hooks 17 and 18, and these enter openings of the side lugs 19 and 20 of an actuating lever 21, which is pivoted at 22 to the lateral pins of a collar 23 arranged on the reduced portion 2 of the handle. A suitable coiled spring 24 is interposed between the collar 23 and the socket 4 of the clamping member 5.

It is readily seen that when the actuating lever 21 is lifted upwardly, the rags of the mop will be gripped securely by means of the corrugations 16 of the clamping frame 12 forcing the same into the transverse bulged out depressions 9 of the sides 6 and 7, and there is no danger of the rags becoming loose or slipping sidewise in the mop head. It is to be understood that slight changes in the details of construction may be made within the scope of the claims.

Having fully described my invention, what I claim is:

1. A mop holder comprising a handle provided with a fixed clamping member, the clamping member having a channeled clamping portion, the opposed walls of said channeled portion having a plurality of opposed depressions, a movable clamping member having a corrugated portion adapted to co-operate with the depressions of said channeled portion, means supporting said movable member, and means for actuating said movable member, substantially as described.

2. A mop holder comprising a handle provided with a fixed clamping member formed of a pair of plates rigidly fastened together, the ends of said plates being bent to serve as guides, and the lower edges of said plates being flared outwardly to form a channeled clamping portion, the opposed flared walls of said channeled portion having a plurality of opposed depressions struck therefrom, a movable clamping member having a corrugated portion adapted to co-operate with the depressions of said channeled portion, arms carrying said movable clamp and slideable in said guides, and means engaged with the ends of said arms for actuating said movable member.

In testimony whereof I affix my signature.

HARRY BREGMAN.
